PAIR OF SPECTACLES

Atherton Mitchell, San Francisco, Calif., assignor, by mesne assignments, to Renaud International, Inc.,
Reading, Pa., a corporation of Pennsylvania

Filed July 7, 1964, Ser. No. 80,736

Term of patent 14 years

(Cl. D57—1)

FIG. 1 is a front perspective view of a pair of spectacles showing my new design;

FIG. 2 is a front view;

FIG. 3 is a side view; and

FIG. 4 is a bottom view.

The dominant features of my design reside in the portions shown in full lines.

I claim:

The ornamental design for a pair of spectacles, as shown and described.
